UNITED STATES PATENT OFFICE.

CHARLES B. LEONARD, OF PHILADELPHIA, PENNSYLVANIA.

LEATHER-STRETCHER DROPPING DEVICE.

1,169,973.

Specification of Letters Patent.

Patented Feb. 1, 1916.

Application filed May 21, 1914. Serial No. 839,925.

To all whom it may concern:

Be it known that I, CHARLES B. LEONARD, a citizen of the United States, and resident of the city and county of Philadelphia and State of Pennsylvania, have invented certain new and useful Improvements in Leather-Stretcher Dropping Devices, of which the following is a specification.

This device is intended to promote the handling of leather stretching boards and is so constructed that the board may be placed in position by a single operator.

In the past the leather stretching boards or planks have been provided with means by which they may be engaged upon an overhead track for the purpose of conveying them to and from a leather stretching machine. The work of disengaging them from the track and placing them upon the leather stretching machine, because of the weight of the boards and clamps contained thereon, has usually been accomplished with much difficulty and by the aid of one or two additional assistants and even then the task was not an easy one and the placing of the boards in proper position required considerable adjustment, man-handling and manipulation.

I have provided a means that will be fully described for accomplishing this work in a very rapid and complete manner, a means that may be operated by a single person and without much difficulty.

My method consists in the employment of what I term a dropping device arranged in line with the leather stretching machine and carrying a portion of the overhead track.

The construction, operation, and advantages to be gained by my device will be fully described as the specification progresses.

The following is what I consider the best means of carrying out this invention.

The accompanying drawings form a part of this specification, in which:

Figure 1. shows an elevation of my device together with certain portions of a leather stretching machine with which it is adapted to operate. Fig. 2. shows the device in a vertical position ready for operation. Fig. 3. shows my device being raised or lowered from or to a vertical position.

Similar reference numerals indicate like parts in all the figures where they appear.

As it is not necessary to change or modify the construction of the leather stretching machine, I have only shown a portion of

one end of the machine and I have indicated by the numeral 1 all of the leather stretching machine that will be found in the drawing. This machine is firm in construction and is provided with certain mechanical devices by means of which the necessary tension may be applied to the leather.

The leather to be stretched is secured upon a plank or board 2, which is provided with a plurality of clamps, the clamps 3 are secured to the board and closely adjacent to one end that I will term the outer end of the board. The clamps 4 are adjustable upon the board to a position that will be determined by the tension applied and the ability of the leather to stretch. The board may also be supplied with supporting webs or cross-bars 5-5. At the inner end of the board a metallic member is secured which forms an eye as indicated at 6 into which a hook 7 may be engaged and it is by the means of the eye 6 and hook 7 that the board is suspended from a traveler 8. This traveler consists of a wheel operable upon a suitably arranged overhead track 9 and when it is desired to transfer or transport the board 2 from or to the stretching machine it is engaged upon the traveler and the wheel traveling upon the track affords an easy means for transferring the board.

The member that I refer to as the "dropping device," consists of a pivoted frame upon which the leather stretching board is adapted to be engaged while the board and frame are in a vertical position. The frame may then be partially rotated lowering the board to a horizontal position and in line with the leather stretching machine.

The dropping device comprises a rectangular floor frame of liberal area as indicated by 10, and upwardly extending therefrom parallel and vertical supports 11 and 12. Through the upper end of these supports a rod 13 is passed, and upon this rod I arrange a plurality of parallel bars 14 and 15. These bars, which may be of angle iron, secured together by suitable cross-pieces 16 and by webs 17 and 18, so that they are held in permanent and firm alinement. Temporarily secured between the angle irons 14 and 15 and adjacent to the lower end thereof, I arrange counterweights 19 which may be any desirable number of solid blocks of metal aggregating a weight sufficient to nearly balance the whole rotatable member upon the rod 13. At the upper end of the

bars 14 and 15 I secure brackets 20 and 21, and between these brackets a short length of track 22 is firmly secured. When the pivotal frame is in a vertical position as shown in Fig. 2 the short length of track 22 coincides with, and becomes a portion of the permanent overhead trolley track 9. When, however, the rotatable frame is in the horizontal position shown in Fig. 1, the removal 10 of the short length of track 22 will leave a gap or space in the track 9. When the rotatable frame supporting the board 30 is lowered to a horizontal position, it may be supported at the proper level by an adjusting 15 or rest-block 23, which may be placed or secured upon one end of the leather stretching machine and upon this block the brackets 20 and 21 will engage with sufficient firmness to support the inner end of the pivotal frame.

To operate my device, a traveler 8 is engaged upon the track 9 and a board 2 is, by means of the eye 6, secured upon the hook 7 which is supported in the 25 traveler 8. The board and traveler are now moved until the traveler is upon the section 22 of the track, and the board is about centered upon the pivotal frame and between the side members or bars 14 30 and 15 thereof. The operator may then pull the frame away from the track and lower it to a horizontal position, with the brackets 20 and 21 resting upon the block 23. In this position the hook 7 may be disengaged 35 from the eye 6, and the traveler removed if this is desirable. The board will then be found to be at rest upon a plurality of rollers 24 and 25 which are supported in brackets 26 and 27, in turn secured to the side 40 frames 14 and 15. A side or sheet of leather may now be engaged in the clamps 3 and drawn across the webs 5—5 to be engaged in the movable clamp 4. In this position the tension creating device of the leather 45 stretching machine is engaged with the clamp 4 and a desirable and necessary strain applied thereto. When the stretching is complete and the clamp 4 has been secured in the ordinary manner, the tension 50 creating means is disengaged and the hook 7, and the traveler 8 returned to position, if they have been removed, and the dropper once more partially rotated on its pivot 13 to the vertical position that will cause the 55 track section 22 to register and coincide with the track section 8 and the board, now supported by the traveler 8 and hook 7, is removed to a convenient drying or storing rack and another board may be placed in 60 position for operation.

The great advantage of my device, is its convenience in operation. It provides a means for the ready handling of that rather awkward member, a leather stretching 65 board, and handles it in a way entirely sat-

isfactory in its operation, and so easy and complete that it reduces to a minimum the placing and removing of leather stretching boards in and from their position of operation adjacent to the stretching machine.

From my description it will be understood that my device will operate with any type of leather stretching machine, and with machines using metallic boards or boards of any weight, size or material. It will also be understood that the device may be used with any known overhead trolley system of the single or double track, round or square barred style, and that the supporting frame may be of a height, and the rotatable frame 75 of a length to allow them to operate successfully regardless of the length of the board, the height of the ceiling or any other permanent dimensions that it is desirable or necessary to consider. Other modifications 80 may be made within the scope of the appended claims without departing from the principle or sacrificing the advantages of the invention.

Having carefully and fully described my 90 invention, what I claim and desire to secure by Letters Patent is:

1. A leather stretcher comprising a board member having a plurality of clamps, a wheel bracket adapted to be temporarily engaged with said board and to support said board, a suspended track along which said bracket may be moved, a stationary frame adjacent to and under said track and having a rotatable portion adapted 95 to receive said board, said rotatable part having a plurality of rollers upon which said board is adjustable longitudinally.

2. A leather stretching device described comprising an overhead trolley track, having a removable section and pivoted and counterweighted stationary support for said removable section, said support being adapted to receive a stretching board and to support it during the stretching operation, as 100 herein specified and for the purpose set forth.

3. A device of the character described comprising a leather stretching board having a traveler temporarily engaged therewith, an overhead trolley track upon which said traveler is adapted to be moved and a removable section in said track independent of said traveler, said section being adapted to be rotated out of or into alignment with 115 said track upon the engagement of the traveler therewith and means for rotating said section out of alignment with said track and into position upon a stretching machine as herein specified and for the purpose set 120 forth.

4. A leather stretcher comprising a track, a bracket having a wheel movable upon said track and a depending hook, a board adapted to be supported upon said hook, said 130

board being provided with a plurality of clamps and a rotatable device supporting a section of said track and adapted to rotate said bracket and the end of the board engaged therewith into a position adjacent to a stretching machine.

5. A leather stretcher comprising a stretching device, a stationary frame adjacent thereto but independent thereof, a 10 portion of said frame being rotatable, and provided with a bracket supporting a sec-

tion of track, and a plurality of rollers, and a board adapted to be movably engaged upon said track section and supported upon said rollers.

Signed at Philadelphia, Penn., this 5th day of May, 1914.
